SADDLE FOR TOP ROLLS

Richard K. Whitehead, Newnan, Ga.

Application March 16, 1949, Serial No. 81,796

14 Claims. (Cl. 19—137)

1

My invention relates to a saddle for the top rolls of spinning and like textile machines.

It is an object of my invention to provide a generally improved saddle for top rolls.

It is another object to provide an improved saddle for top rolls involving two saddle blocks having improved means for securely though detachably holding the saddle blocks together.

It is another object to provide an improved saddle for top rolls, which will be substantially non-linting.

Still another object is to provide an improved saddle for top rolls in which the bearings will be self-lubricating and which will have extremely long life.

A further object is to provide a saddle which will not cut the top roll journals when the bearings wear down so as to drop the saddle blocks directly onto the roll journals.

It is another object to provide an improved bearing block member for top roll saddles, cap bar nibs and the like, which will be self-lubricating, non-soiling, and have extremely long life, and in which friction will be reduced to a minimum.

It is another object to provide an improved saddle for top rolls, which will jackknife readily to permit lifting up of any one of the top rolls.

Other objects and various features of novelty and invention will be hereinafter pointed out or will become apparent to those skilled in the art.

In the drawings which show, for illustrative purposes only, preferred forms of the invention—

Fig. 1 is a side view in elevation of one form of my improved saddle for top rolls, showing the saddle in place on top rolls, and showing the stirrup engaging a conventional type of weight lever;

Fig. 2 is a central, longitudinal sectional view through the saddle shown in Fig. 1, the stirrup being broken away;

Fig. 3 is a bottom plan view of the saddle shown in Fig. 2;

Fig. 4 is a sectional view on an enlarged scale, taken substantially in the plane of the line 4—4 of Fig. 2;

Fig. 5 is a bottom plan view on an enlarged scale of a front saddle block, a part of one side flange being shown in section;

Fig. 6 is a sectional view, taken substantially in the plane of the line 6—6 of Fig. 5;

Fig. 7 is a perspective view of a bearing block, typical of bearing blocks, to be used in my improved saddle;

Fig. 8 is a view in side elevation of a saddle like

those heretofore shown, but illustrating a different form of stirrup;

Fig. 9 is a view in side elevation of a jump saddle illustrating features of the invention;

5 Fig. 10 is a bottom plan view of the jump saddle shown in Fig. 9, the stirrup being omitted; and

Fig. 11 is a view in side elevation of a two-roll saddle for use in a self-weighted center roll system.

10 In said drawings, 5—6—7 indicate the front, center, and rear driven rolls of a drawing system, while 8—9—10 indicate the top rolls having the front journal 11, center journal 12, and rear journal 13, upon which journals my improved saddle is adapted to rest.

My improved saddle includes a front saddle block 14 and a back saddle block 15. The front saddle block is of generally curved or arcuate shape in longitudinal section, so as to provide a smooth surface, without projections, to avoid linting. The block 14 is preferably formed of die-cast, high-strength aluminum, and since it is preferably die-cast, it may be very accurately formed so that all parts designed to fit therewith

15 may fit with exact nicety. At the front, the saddle member 14 has a front bearing block 16, which, as will be later described, is forced into a pocket or recess die-cast in the saddle block. The front saddle block 14 is provided with a longitudinally extending narrow channel 17, which

20 is of a width snugly to receive a stirrup 18, which may be of flat stock. The saddle block 14 is provided with a plurality of sets of holes 19 for the reception of a pivot pin 20 for pivotally supporting the stirrup 18 in the saddle block 14. The stirrup 18 may be curved, as shown in Figs. 1 to 4, or may be straight, as shown in Fig. 9, or may be otherwise shaped, as shown, for example, in Figs.

25 8 and 11, to fit different spinning systems, all as will be understood. At each side of the channel and defining the lower limits of the channel are bearing surfaces or lands 21—21 extending longitudinally and substantially to the rear of the saddle block 14. These bearing surfaces are designed to support the back saddle block 15.

The back saddle block 15 is preferably also of die-cast aluminum, and in the preferred form has a shaped bearing block 22 for engaging the journal of the rear top roll, and a flat bearing block 23 for engaging the center top roll. The back saddle block preferably has a rounded or generally arcuate bearing surface 24 for fitting on the bearing surface or surfaces 21 of the front saddle block.

55 I employ novel means to hold the front and

back saddle blocks in detachably, though securely, assembled relationship. The front block, in the preferred form, has downwardly extending longitudinal flanges 25—25 for rather snugly embracing the sides of the back saddle block 15. One of the blocks (in this case the front saddle block 14) has grooves 26—26 milled or otherwise formed therein, on the inner sides of the flanges and facing each other. The other block (in this case the back block 15) has projecting means which may be in the form of integral bosses 27—27 for fitting in the grooves 26. In the preferred form, the grooves 26—26 are of considerable vertical extent and considerably larger than the bosses 27—27, so that the back saddle member 15 may move up and down, as well as longitudinally, of the front saddle block 14, and may also pivot freely therein so that the saddle may be jack-knifed when occasion requires. The bosses 27—27 are of such an extent, and the flanges are so formed, that when the two saddle parts may be forcibly engaged with each other, the bosses will spring the flanges 25 apart sufficiently so as to permit entry of the bosses in the grooves 26—26. The saddle blocks may be separated from each other by merely pulling them apart, thus spreading the flanges 25—25 and permitting the bosses to leave the grooves 26—26. As shown, particularly in Fig. 4, the side flanges 25—25 adjacent the edges turn inwardly to form abutments to be engaged by the abutment means 27—27 which are wider than the space between the inturned edges of the flanges. Thus the saddle blocks are loosely held together.

When the stirrup is of the form shown in Fig. 8, the back saddle block 15 need not be slotted, as shown at 28, for the passage of the stirrup 18. For the sake of uniformity, both saddle blocks 14—15 may be formed as shown in Figs. 1 to 4, regardless of the type of stirrup, though, of course, if stirrups of the types shown in Figs. 8—11 are to be employed, there is no real necessity for slotting the rear block 15, nor for extending the channel 17 for the stirrup as far back as has been shown in Fig. 2. It will be seen, then, that since the saddle blocks 14—15 fit each other quite snugly and since the stirrup 18 fits the channel 17 quite snugly, there is substantially no chance for the saddle to turn over when it is engaged with the top roll journals. Furthermore, since the bottom of the stirrup has a hole for fitting the weighting lever 29 quite snugly, there is substantially no chance for the saddle to wander back and forth on the top roll journals.

The bearing blocks which I prefer to employ are formed of wood or other fibers, suitably held together and presented to the top roll journals on end grain. Wood, impregnated with oil, and presented end grain to the top roll journals, will be relatively frictionless and will be self-lubricating. It should be understood that, when the bearing blocks are presented on end grain to the top roll journals, substantially the entire surface of the bearing block will be a lubricating surface, since oil or other lubricant may flow down the capillaries, over the entire end grain surface in contact with the rolls, whereas, if the bearing blocks were presented on side grain to the rolls, there would be very few capillary passages in contact with the roll journals, and likely the lubricant would be insufficient. In addition to providing bearing blocks of good bearing wood impregnated with oil or other lubricant, I contemplate the employment of other fibers, prefer-

ably cellulose fibers, held together as by means of a phenolic condensation product, impregnated with oil or other lubricant. The bearing blocks, in any event, are preferably presented to the top roll journals on end grain so as to provide the self-lubricating bearing blocks, as heretofore noted. These bearing blocks of wood or other fiber, preferably cellulose suitably held together and presented on end grain, will be highly useful, and I contemplate using them, in the cap bars in which the ends of the top rolls are guided. The cap bar nibs are presented on end grain and will be self-lubricating. The amount of oil or other lubricant exuding from the bearing blocks will be slight, yet sufficient. The amount will never be sufficient to overrun and soil the yarn, and yet will be sufficient to lubricate the journals for substantially the life of the bearing blocks. A typical bearing block of wood or other fiber on end grain is shown in Fig. 7, wherein the block has a generally rectangular base as shown at 30, and in the particular form shown is formed as at 31 to fit over a journal. It will be clear from that figure that substantially the entire surface of the bearing block in contact with the journal will be a capillary contact to provide lubrication.

My improved blocks are preferably formed to size with reasonable accuracy. As has been heretofore stated, the blocks, such as 16, 23, and 22 of the saddle heretofore described are held in recesses in the saddle blocks. Such bearing blocks are preferably of the types heretofore described. All of the saddle parts which are designed to receive bearing blocks are preferably formed by die-casting and are quite accurately formed. As shown in Fig. 5, I provide means for securely holding the bearing blocks in place without damage either to the saddle block or to the bearing block. In the form illustrated particularly in Figs. 5 and 6, the recess 32, which may be considered as typical of all of the recesses in the various saddles described, or to be described, may be of angular shape, or of any desired shape, so long as the bearing blocks are of substantially corresponding shape. As shown, the recess 32 has small projections 33—33, preferably pointed toward the open ends of the recesses and projecting inwardly into the recesses. These projections are shown in Figs. 5 and 6 in somewhat exaggerated form, since they need not be actually as large as shown. When the bearing blocks are forced into the recesses, the projections 33 will bite into the bearing blocks, particularly if they be presented end grain, and the bearing blocks will be very securely held in place. The sides of the recesses 32 will give adequate support to the bearing blocks so that there will be no danger of splitting of those bearing blocks when forcing the same into the recesses, or when in use. If the bearing blocks should wear out, or if for any reason it is desired to remove a bearing block, the saddle blocks are provided with holes 34 through which a drift pin may be passed for driving the blocks out.

In the saddle shown in Fig. 8, all of the parts are substantially the same as those heretofore described, except that the stirrup 18' is of a different form.

In that form of the invention shown in Figs. 9 and 10, I illustrate a jump saddle which is employed in a self-weighted center roll system. As shown in Figs. 9 and 10, the jump saddle comprises a single saddle part 40, having a front bearing to engage the front roll journal 11', and having one or a plurality of rear bearings 41

for engaging the rear roll 13". The center roll 12", in this instance, is of the self-weighted type and is not engaged by my jump saddle. The saddle is provided with a channel 42 for snugly receiving the top of a stirrup 43, and the saddle is provided with a plurality of holes 44 for receiving a pin 45 for adjustably and pivotally supporting the stirrup in the saddle 40.

In that form of the invention shown in Fig. 11, I show a two-roll saddle employed somewhat after the manner of a jump saddle, wherein there is a self-weighted center roll. The front saddle block 46 may be a duplicate of the saddle block shown in Fig. 2, and the rear saddle block 47 may be a simple block corresponding to the rear saddle block 15, but being provided with a single bearing block 48. The rear saddle block 47 is preferably not pivotally mounted, but has a flat, upper surface to ride on the flat surface 49, corresponding in general to the surface 24 heretofore described. The flanges may be provided with grooves 50, and the rear saddle block 47 may be provided with bosses 51 corresponding to the grooves 26 and bosses 27, heretofore described. Thus, the front saddle 46 may have a front bearing to engage the front roll 11", and the rear saddle block 47 may have a single bearing 48 to engage the rear roll 13", while the middle roll 12" is preferably self-weighted.

The front and back saddle blocks and the single block of Fig. 9, as heretofore stated, are preferably formed of die-cast aluminum. The parts may be very accurately made so that all fits may be as close as desired. Thus, the saddles will be substantially non-tipping and non-wandering and wear will be reduced. The die-cast parts may be tumbled, buffed or polished so as to be very smooth on the outside and thus avoid linting up and facilitate cleaning.

With my improved self-lubricating bearing blocks, no outside lubrication is required and there is no chance of soiling the yarn through over-lubrication or leakage of lubricant. The bearing blocks will be very firmly held in their recesses but may be easily knocked out and replaced when required.

My improved saddle consists of but few parts, and by variously combining parts, saddles may be provided for serving in almost all of the spinning systems. All of the parts may be very readily assembled. When the type stirrup is selected, and its position determined, it is only necessary to drive a pin in place so as to pivotally secure the stirrup permanently and pivotally where desired. The front and back saddle blocks may be snapped together or snapped apart from each other, and yet when the saddle blocks are engaged with each other, they will be sufficiently securely held together and yet will be so loosely held that the saddle parts may adjust themselves on the rolls with great readiness, and the saddle will jackknife with the greatest ease, when jackknifing is called for, as when one of the roll ends is picked up for cleaning one of the cap bar bearings.

My saddle blocks are formed of a material softer than the top roll journals so that if the bearing blocks should wear down so as to drop the saddle blocks onto the roll journals, the softer blocks will be worn and the harder and more expensive top rolls will not be damaged. When the rolls are formed of cast iron, my saddles may be made of die-cast aluminum, as described, or of other relatively soft, yet strong material.

While the invention has been described in con-

siderable detail and preferred forms illustrated, it is to be understood that various changes may be made within the scope of the invention as defined in the appended claims.

5 I claim:

1. In a saddle for top rolls, a front saddle block, a rear saddle block, said rear saddle block having a bearing surface for rockably engaging said front saddle block, said front saddle block including side flanges extending downwardly over said back saddle block, one of said saddle blocks having a longitudinally extending groove therein, and the other of said saddle blocks having a boss projecting into said groove for loosely supporting said back saddle block in said front saddle block, said projecting boss being of a size to spring one of said saddle members sufficiently to permit said boss to enter said groove.

2. In a saddle for top rolls, a front saddle member, a back saddle member, said front saddle member having downwardly extending flanges to embrace said back saddle member, said front saddle member having bearing surface means for rockable engagement by said back saddle member, said flanges having grooves therein on the inside and facing each other, said back saddle member having projecting bosses to fit in said grooves for loosely holding said front and back saddle members together.

3. In a saddle for top rolls, a front saddle block, a rear saddle block, said front saddle block having longitudinally extending downwardly projecting flanges to embrace said back saddle block, said front saddle block having a longitudinally extending channel extending longitudinally and centrally thereof and opening at the bottom of said front saddle block, said channel being of a size to snugly receive a stirrup, said front saddle member having holes for receiving a pivot pin for pivotally supporting a stirrup on said front saddle member, said front saddle member having longitudinally extending bearing surface means at opposite sides of said channel, said back saddle block having rounded bearing surface means for engaging the bearing surface means on said front saddle block, whereby said back saddle block will be rockably supported on said front saddle block, and means for holding said saddle blocks in loosely assembled relationship.

4. In a saddle for top rolls, a front saddle block, a rear saddle block, said front saddle block having longitudinally extending downwardly directed flanges to embrace said rear saddle block, said flanges having longitudinally extending grooves on the inner sides thereof and facing each other, said back saddle block having outwardly directed bosses thereon to fit in said grooves, said grooves being of a substantially greater vertical extent than the vertical extent of said bosses, whereby said saddle blocks may have substantial vertical movement relatively to each other, said bosses being of an extent to cause the outwardly springing of said flanges to permit said bosses to enter said grooves.

5. In a saddle for top rolls, a front saddle block having a bearing block at the front end thereof, a rear saddle block having a rear bearing block therein, said front saddle block having a bearing surface on the underside thereof and downwardly extending flanges at the outer sides of said bearing surface, said rear saddle block having a top surface for rockable engagement with said bearing surface on said front saddle block, one of said saddle blocks having longitudinally extending grooves therein, the other of said saddle blocks

having bosses to fit within said grooves for loosely holding said bearing blocks together.

6. In a saddle for top rolls, a saddle block having a front bearing block carried thereby at the front end, said saddle block having a deep, longitudinal channel on the underside thereof of a size to snugly embrace the sides of a stirrup whereby the stirrup cannot swing sidewise of said saddle block, said saddle block having a hole for receiving a pin for pivotally supporting a stirrup for longitudinally swinging in said channel, and means for supporting bearing block means for engagement with a rear top roll journal.

7. In a saddle for top rolls, a front saddle block of die-cast material and comprising a unitary one-piece integral block, said block having a recess at the forward end for receiving a bearing block, said saddle block having a longitudinally extending channel central of the underside thereof and of a width to snugly receive a stirrup, said saddle block having longitudinally extending bearing surfaces at opposite sides of said channel, said saddle block having downwardly extending flanges at the outer sides of said bearing surfaces, said flanges having longitudinally extending grooves on the inner sides and facing each other, a back saddle block fitting between and embraced by said flanges, said back saddle block having bosses projecting therefrom and fitting in said grooves, for the purpose described.

8. In a saddle for top rolls, a front saddle block, a rear saddle block, one of said blocks having longitudinal side flanges to embrace the other block between them, one of said blocks having laterally projecting bosses and the other of said blocks having lateral grooves to receive said bosses to loosely support said blocks one from the other, said coacting bosses and grooves being between said flanges so as to avoid exterior openings or projections to collect lint.

9. In a saddle for top rolls, a front saddle block, a rear saddle block, one of said blocks having longitudinal side flanges to embrace the other block between them, means for loosely supporting said blocks one from the other, comprising interfitting bosses and recesses, said interfitting bosses and recesses being between said flanges so as to avoid exterior openings or projections to collect lint.

10. In the combination defined in claim 9, said interfitting bosses and recesses being of a size to spring into coacting relation upon a movement of said flanges.

11. In a saddle for top rolls, a front saddle block, a rear saddle block, said front saddle block having depending side flanges embracing said rear saddle block, said rear saddle block having a surface to rockably engage said front saddle block between said flanges, the under side of said front saddle block having a longitudinal groove therein to snugly receive a stirrup, means for pivoting the stirrup in said groove, said rear

saddle block having a vertical slot therethrough for the passage of the stirrup pivoted in said groove, and means for loosely supporting said front and rear saddle blocks one from the other.

12. In a saddle for top rolls, a front saddle member, a rear saddle member, said front saddle member having downwardly directed side flanges, said rear saddle member being positioned between said side flanges, and in rocking engagement with said front saddle member, said side flanges at the bottom having generally inwardly directed abutments, said rear saddle member having abutment parts extending outwardly beyond the inner sides of said inwardly directed abutments on said flanges, said abutments on said flanges and on said rear saddle member coacting with each other to hold said saddle members against separation, roll bearing block means on said saddle members, and a stirrup pivotally connected to said front saddle member.

13. In a saddle for top rolls, a front saddle member, a rear saddle member, one of said saddle members having side flanges, the other saddle member being positioned between said side flanges, said side flanges adjacent the edges having generally inwardly directed abutments, said saddle member between said side flanges having abutment means extending outwardly beyond the inner sides of said inwardly directed abutments on said side flanges, said abutments on said two saddle members coacting with each other to hold said saddle members against separation.

14. In the combination defined in claim 13, said front saddle member having a generally rounded top and a deep longitudinally extending channel beneath said top and opening downwardly, a stirrup extending into said channel, means for pivotally mounting said stirrup in said channel; and roll bearing engaging parts on said saddle members.
